(57) **CLAIM**

The ornamental design for a container, lid and refill, as shown and described.

DESCRIPTION

FIG. 1 is a top perspective view of a container, lid and refill showing our new design;

FIG. 2 is a top plan view thereof;

FIG. 3 is a front elevation view thereof;

FIG. 4 is a bottom plan view thereof;

FIG. 5 is a top perspective view of the container member;

FIG. 6 is a top plan view thereof;

FIG. 7 is a bottom plan view thereof;

FIG. 8 is a front elevation view thereof;

FIG. 9 is a side elevation view thereof;

FIG. 10 is a top perspective view of the refill member;

FIG. 11 is a front elevation view thereof;

FIG. 12 is a top plan view thereof;

FIG. 13 is a bottom plan view thereof;

FIG. 14 is a top perspective view of the lid member;

FIG. 15 is a front elevation view thereof;

FIG. 16 is a top plan view thereof;

FIG. 17 is a bottom plan view thereof; and,

FIG. 18 is another perspective view thereof in an exploded condition.
